CIGARETTE

Rowland Frank May, Potters Bar, England, assignor to Filter Tips Limited, London, England, a company of Great Britain

Application November 7, 1934, Serial No. 751,950
In Great Britain November 9, 1933

4 Claims. (Cl. 93—1)

This invention relates to cigarettes and is more particularly concerned with the production of filter tip cigarettes in which the filter tip or equivalent mouthpiece insertion is formed by transversely folding a length of strip material.

The invention has among its objects to provide an improved method of and means for producing such filter tips or like insertions whereby filter tips of definite cross-sectional formation may be readily produced at high speed and, further, to provide a filter tip or like insertion having a folded formation requiring the minimum of subsequent compression for retaining or consolidating its circular, or substantially circular, cross-section prior to its incorporation in the cigarette or cigarette paper tube or mouthpiece.

According to the present invention, a method of producing filter tips or like mouthpieces for cigarettes consists in subjecting a length of strip material to the action of a series of folding devices arranged successively at right angles, or substantially so, whereby the strip is folded transversely in stages and the folded strip is positioned in relation to the folding device next in series or in a final receiving chamber.

The invention moreover includes a method of producing filter tips or like mouthpieces for cigarettes consisting in subjecting lengths of strip material to the action of a plurality of folding devices operating successively on each strip in such manner that each strip is folded transversely in stages, and feeding a length of the material to the first folding device at each stroke or operation thereof so that more than one length of material is simultaneously subjected to folding operations and so that at each stroke or operation of the folding devices a complete filter tip or like mouthpiece is produced.

According to the invention moreover apparatus for the production of filter tips or like mouthpieces comprises a series of folding devices arranged successively at right angles to one another and arranged so that the folded formation produced by one folding device is positioned in relation to the folding device next in series or in a final receiving chamber. The folding devices may comprise reciprocatable or oscillatable blades co-operating with slots or the like. The slots or the equivalent are shaped or adapted to provide reduced or constricted inlets thereto to ensure retention of the folded formation in the slot while the respective folding blade is withdrawn. The blade of the final folding device may be mounted in a member adapted, in conjunction with the final receiving chamber,

to provide a more or less complete bore from which the folded filter tip formation is ejected axially by means of a suitable plunger.

The means for feeding lengths of strip material to the folding unit may operate in such manner that a length of strip material is fed to the first folding device at each stroke or operation thereof so that more than one length of material is subjected to folding operations in the folding unit at the same time. The strip material may be fed continuously by means of feed rollers and may be cut into successive lengths by means of a quick-action cutter. The cutter advantageously is a rotary cutter having a comparatively narrow cutting blade.

The folding devices may be arranged to produce various folded formations. In one preferred arrangement a strip of material is subjected successively to the action of three folding blades arranged successively at right angles, the first and third blades acting in opposite directions. In a modification the strip material is subjected to the action of three folding blades arranged successively at right angles, the first and third blades acting in the same direction.

The invention is hereinafter described by way of example with reference to the accompanying diagrammatic drawings, in which:

Figure 1 is a side elevation illustrating one construction of apparatus in accordance with the invention;

Figure 2 is an end elevation corresponding to Figure 1;

Figure 3 is a section on the line III—III, Figure 1;

Figure 4 is a sectional elevation of the folding unit and feed and cut-off mechanism showing the positions of the parts at the commencement of the folding operation on a strip;

Figure 5 is a view similar to Figure 4 showing the positions of the parts at the end of the first folding operation;

Figure 6 is an end elevation on an enlarged scale illustrating the approximate folded formation produced in the arrangement of Figures 1 to 5;

Figure 7 is a view similar to Figure 4 illustrating a modification; and

Figure 8 is an end elevation on an enlarged scale illustrating the approximate folded formation produced in the arrangement shown in Figure 7.

In carrying the invention into effect according to one embodiment and referring more particularly to Figures 4, 5 and 6 of the accom-

panying diagrammatic drawings, a strip 1 of material is acted on successively by folding blades 2, 3, 4 whereby the material is folded upon itself substantially at a middle position in the length at each operation. For instance, a length 1 of material fed from a supply spool (not shown) and cut off by a suitable cutting device 5 is located so that the mid point in its length is disposed over a transverse slot 6a in a folding unit member 6, into which slot 6a the strip 1 is folded by means of the reciprocatable blade 2. The folded strip 1 is located in the slot 6a so that the mid point of its length is opposite a laterally extending slot 6b of increased width into which the material is folded by the second reciprocatable blade 3 operating in a plane at right angles to the blade 2. In the second slot 6b the folded material is located so that the mid point of its length is disposed opposite a third slot 6c of increased width into which the material is folded by the reciprocatable blade 4 disposed parallel with the blade 2 and acting in the opposite direction thereto, the blade 3 operating when the first and third blades 2 and 4 are withdrawn. The slot 6c terminates in a tubular receiving chamber 6d from which the completed folded filter tip formation 1a is ejected by means of a plunger 7 into a receiving tube 1c from which it may be delivered into chambers in an intermittently rotatable drum 8 or other carrier or conveyor or into a receiving spoon for transfer into a cigarette, or such tube 1c itself may be constituted by a spoon whereby the filter tip may be inserted into a cigarette. The blade 4 may be carried by a member 4c which at its upper end is shaped so that when in the position shown in Figure 5 it provides, in conjunction with the chamber 6d, a more or less complete bore in which the folded filter tip formation 1a is shaped to an approximately circular cross-section prior to ejection by the plunger 7.

In order to avoid any possibility of the folded material being retracted from the slots 6a, 6b, 6c on withdrawal of the respective blades 2, 3, 4, the inlet to each slot is reduced in width or otherwise adapted to form narrow necks 2', 3' and 4', respectively. The material, owing to its natural tendency to expand after passing such neck, is held by said narrow necks against return movement during withdrawal of the respective blade.

It will be seen, by reference to Figures 4 and 5, that at the same time as a strip 1 is being folded into the slot 6a by the blade 2, a previously folded strip located in the slot 6b is folded into the slot 6c and thence into the chamber 6d by the blade 4. Similarly, at the same time as the folded length in the slot 6a is carried into the slot 6b by the blade 3, the final folded formation in the chamber 6d is ejected by the plunger 7. Thus, there are always two lengths of material in the complete folding unit and consequently it is possible to feed a strip of material to the first folding device at each stroke or operation thereof and likewise to produce a complete filter tip at each stroke or operation.

The folding blades and the feeding, cutting-off mechanism and ejecting mechanism may be arranged and constructed in any suitable manner.

For example, as shown more particularly in Figures 1, 2 and 3, the blades 2, 3, 4 may be adjustably carried by slides 2a 3a, 4a. The slides 2a and 3a are connected by links 2b, 3b respec-

tively to a bell crank lever 9 mounted on a shaft 10 which is oscillated by means of a crank 11a through a link 11b and arm 10a, the crank 11a being mounted on a shaft 11 disposed parallel with the shaft 10 and carried in bearings in opposite walls of the frame 12. The slide 4a is connected by means of a link 4b to a bell crank lever 13 oscillatable on a pivot 13a, the upwardly extending arm of the lever 13 being connected to an eccentric strap 14a co-operating with an eccentric 14 on a shaft 15 arranged at right angles to the shaft 11 and driven therefrom by the co-operating bevel gears 11c, 15a. The ejecting plunger 7 is connected by a transverse pin 1b to twin eccentric straps 16a co-operating with twin eccentrics 16 mounted on the shaft 15, the plunger 7 being slidable in a fixed guide 17 mounted co-axially with the receiving chamber 6d. The feed of the strip material to the folding unit is effected by rollers 18, 18a geared together by gears 19, 19a and driven through the gear 19b on the spindle of the lower roller 18a and a gear 11d on the shaft 11. The rollers 18, 18a are formed with circumferential slots 18b for the accommodation of ribs 20a projecting from a fixed guide 20 so that the material is directed positively to the folding unit. The strip material is guided to the rollers 18, 18a by means of a feed tray 21.

The cutter 5 which is in the form of a comparatively narrow blade is mounted on a disc 5a carried by a shaft 22 provided with a gear 22a meshing with a gear 23 rotatable on a fixed bolt or pin 23a which gear 23 in turn meshes with a gear 15b on the end of the shaft 15. A fixed blade 24 is arranged to co-operate with the cutter 5 and is carried by a support 24a. A guide 6e may be arranged to ensure correct positioning of the strip material above the slot 6a.

The mechanism described may be driven by means of a gear 25a mounted on a shaft 25 and meshing with a pinion 11e on the shaft 11, the gear 25a being in turn driven by a pinion 26a on a shaft 26 which may be connected up to a suitable power drive and/or to other mechanism with which the apparatus described has to operate in timed relation.

As indicated in Figure 4, the mechanism is timed so that the blade 2 engages the length 1 of strip material practically at the same time as the cutter 5 severs the length from the continuous strip fed forward by the rollers 18, 18a.

In a modification as illustrated in Figure 7, the final folding blade 4 is arranged to operate in the same direction as the blade 2, thereby producing a folded formation approximately as shown in Figure 8. In this arrangement the folded material may be ejected from the third slot by the action of the third blade into a fixed or moving channel which may be constituted by the suitably guided paper strip of a continuous rod machine provided with means for forming spaces in the tobacco filling for the reception of the filter tips or with means for subsequently depositing lengths of tobacco between the filter tips applied on the paper strip.

What I claim is:—

1. An apparatus for forming paper wads comprising a block having a downwardly extending recess, a horizontal recess extending from the mid-depth of the downwardly extending recess, a vertical recess extending from the mid-portion of the horizontal recess, a substantially cylindrical molding chamber formed as a continuation of said vertical recess, plungers cooperating

with said recesses to fold and insert a sheet of material into the first recess and fold and transfer the same serially to the molding chamber, a bell-crank lever, a link connecting one end of said lever to the plunger cooperating with the downwardly extending recess, a link connecting the other end of said lever with the plunger cooperating with the horizontal recess, a shaft for rocking said lever, and means for transmitting rotary motion from said shaft to reciprocatory motion of the plunger cooperating with said vertical recess.

2. An apparatus for forming paper wads comprising a block having a downwardly extending recess, a horizontal recess extending from the mid-depth of the downwardly extending recess, a vertical recess extending from the mid-portion of the horizontal recess, a substantially cylindrical molding chamber formed as a continuation of said vertical recess, plungers cooperating with said recesses to fold and insert a sheet of material into the first recess and fold and transfer the same serially to the molding chamber, a bell-crank lever, a link connecting one end of said lever to the plunger cooperating with the downwardly extending recess, a link connecting the other end of said lever with the plunger cooperating with the horizontal recess, a rock shaft carrying said bell-crank lever, a rotary shaft, a crank affixed to said rotary shaft, a crank affixed to said rock shaft, a link connecting the free ends of said cranks to transfer rotary motion of the rotary shaft into rocking motion of the rock shaft, and means for transmitting rotary motion of the rotary shaft to reciprocatory motion of the plunger cooperating with the vertical recess.

3. An apparatus for forming paper wads comprising a block having a downwardly extending recess, a horizontal recess extending from the mid-depth of the downwardly extending recess,

a vertical recess extending from the mid-portion of the horizontal recess, a substantially cylindrical molding chamber formed as a continuation of said vertical recess, plungers cooperating with said recesses to fold and insert a sheet of material into the first recess and fold and transfer the same serially to the molding chamber, a bell-crank lever, a link connecting one end of said lever to the plunger cooperating with the downwardly extending recess, a link connecting the other end of said lever with the plunger cooperating with the horizontal recess, a rotary shaft, means for transmitting rotary motion from said shaft to rocking motion of said bell-crank, and means for transmitting rotary motion from said shaft to reciprocatory motion of the plunger associated with the vertical recess in synchronism with the plunger of the downwardly extending recess.

4. An apparatus for forming paper wads comprising a block having a downwardly extending recess, a horizontal recess extending from the mid-depth of the downwardly extending recess, a vertical recess extending from the mid-portion of the horizontal recess, a substantially cylindrical molding chamber formed as a continuation of said vertical recess, plungers cooperating with said recesses to fold and insert a sheet of material into the first recess and fold and transfer the same serially to the molding chamber, means for ejecting the molded formation axially from the molding chamber, means for effecting simultaneous folding movement of the plungers cooperating with said downwardly extending and vertical recesses, and means for effecting simultaneous folding movement of the plunger cooperating with the horizontal recess and ejecting action of the ejecting means.

ROWLAND FRANK MAY.
